By Attorney
Richard J. Cook

UNITED STATES PATENT OFFICE.

DANIEL P. VICK, OF SEATTLE, WASHINGTON.

DESIGN FOR A COMBINATION LIFTING-JACK AND VISE.

58,646.

Specification for Design.

Patented Aug. 2, 1921.

Application filed August 10, 1920. Serial No. 402,705. Term of patent 14 years.

To all whom it may concern:

Be it known that I, DANIEL P. VICK, a citizen of the United States, residing at Seattle, in the county of King, State of Washington, have invented a new, original, and ornamental Design for a Combination Lifting-Jack and Vise, of which the following is a specification, reference being had to the accompanying drawing, forming part thereof.

Figure 1 is a side elevation of the device.
Fig. 2 is a front view of the same.

Fig. 3 is a plan view of the same.

I claim:

The ornamental design for a combination lifting jack and vise as shown.

DANIEL P. VICK.
